UNITED STATES PATENT OFFICE.

CHARLES MAY, OF NEW BRITAIN, CONNECTICUT.

VENDING MACHINE.

Application filed November 6, 1918. Serial No. 261,348.

To all whom it may concern:

Be it known that I, CHARLES MAY, a citizen of the United States, and a resident of New Britain, in the county of Hartford and 5 State of Connecticut, have invented a new and Improved Vending Machine, of which the following is a specification.

My invention relates to the class of devices above named, and an object of my 10 invention, among others, is to provide a machine of this class that shall be extremely simple in construction and simple and effective in operation.

One form of vending machine embodying 15 my invention and in the construction and use of which the objects herein set out, as well as others, may be attained, is illustrated in the accompanying drawings, in which—

Figure 1 is a view in front elevation of a 20 vending machine embodying my invention.

Figure 2 is a view in vertical section through the same generally on plane denoted by dotted line 2—2 of Figure 1, this 25 plane being diverted enough to pass longitudinally through the coin chute.

Figure 3 is a top plan view of the 30 machine with the cover removed and with parts broken away to show construction, the point of view being illustrated by the dotted line 3—3 of Figure 2 and the standard and base being omitted.

Figure 4 is a view of a part of the receptacle on enlarged scale.

Figure 5 is a detail view in section on 35 plane denoted by dotted line 5—5 of Figure 4, parts at the back being omitted.

Figure 6 is a detail view, scale enlarged, illustrating the mouth of the coin chute and the coin carrier.

40 Figure 7 is a detail view illustrating the mechanism for denoting the number of articles to be obtained for a coin.

My improved vending machine is not limited in the nature of its use and may be employed for vending merchandise or articles of various descriptions, but, as I have found it particularly useful for vending matches put up in the so called "book-form" I have 45 illustrated and described my invention herein as embodied in a machine constructed to receive such packages of matches or articles of a similar nature, which machine comprises a case 10 mounted on a standard 50 rising from a base 12. These parts may 11 be constructed of any suitable material preferably sheet metal, bent to proper form and

they may be of any desired form or shape in cross section. As shown herein the case is round and it is mounted on the standard in an inclined position, the exact angle of 60 such inclination not being of extreme importance, an angle of approximately forty-five degrees having been found by me to produce the best results. The standard has a recess 13 opening to the front into which 65 the articles fall when released from the case and through which opening they may be obtained. A coin chamber 14 is formed in the back part of the standard, the bottom of this chamber preferably sloping rearwardly to cause the coins to slide outwardly 70 from the chamber when the door 15 is opened.

A receptacle 16 is rotatably mounted in 75 the case, preferably upon a post 17 secured to the bottom of the case in any suitable manner, as herein shown a nut fitting the threaded end of the post being employed. This receptacle comprises a drum 18 having plates extending radially therefrom, and forming pockets 19 radially disposed thereabout. The plates extend nearly to the inner surface of the wall of the case and as herein shown they are formed in pairs, each pair of plates comprising a piece of metal 80 bent into U-shape as shown in Figure 3 of the drawings.

The drum incloses an inner chamber 20 at the center of the case and an indexing plate 21 is secured within the outer end of said 90 drum and at the mouth of said chamber. This indexing plate has indexing slots 22, equal in number to the pockets 19, said slots being preferably disposed in radial lines.

A detent lever 23 is pivotally mounted on 95 a support 24 secured to the bottom of the case and rising therefrom, said support having a coin table 25 at its upper end. The detent lever is mounted underneath said table and has a detent 26 projecting through 100 an opening in the table and into the indexing slots 22. A trip 27 also projects from the lever through an opening in said table into the path of movement of a coin inserted through a coin slot 28 through a cover 29 of 105 the case. The trip 27 is beveled on its upper edge, against which beveled surface a coin rests when inserted through said coin slot. A discharge opening 30 is formed through the bottom of the case, this opening being of 110 a width approximately that of the pockets 19.

A coin discharge opening 31 is formed through the table 25 at a point near the trip 27, and a coin chute 32 extends from said coin discharge opening to the chamber 5 14. A coin carrier 33 is pivotally attached to the under side of the cover 29, this carrier having a coin opening 34 for the reception of a coin deposited in the slot 28. The carrier is held at one limit of its play as by 10 means of a spring 35. An actuating knob 36 projects from the carrier through a slot in the cover to the outside thereof and a thumb or finger rest 37 is secured to the cover and serves as a support for the finger 15 or thumb in the operation of the device, which, thus far described, is as follows:

The pockets in the carrier being filled with books of matches, say two to a pocket, and the case being closed, a coin is deposited in 20 the coin slot 28, said coin dropping through said slot and resting in a coin recess 53 in the carrier 33, the lower edge of said coin resting upon the upper end of the trip 27 or the upper surface of the table close to 25 said trip. In this position of the parts the detent 26 holds the receptacle against rotation. When the coin has been thus deposited the thumb, of the right hand if used, is placed against the rest 37 and the forefinger against the knob 36. Pressure now 30 applied to the knob will force the carrier towards said rest, carrying the coin with it and sweeping it across the beveled upper end of the trip, the coin being held from outward movement by contact with the top of the recess 53 in the carrier in which it is located. The trip is thus forced downward, disengaging the detent 26 from the indexing slot 35 22 which it occupies at that time, one edge of said detent being beveled to facilitate movement of the receptacle after the detent has been moved downwardly to a proper extent, at which time the edge of a slot 22, may come in contact with said beveled surface, and force the detent and its lever downwardly far enough to permit the receptacle 40 to rotate to the proper degree.

This rotation of the receptacle is caused by the carrier 33 through the medium of the 45 coin located in one of the slots 22, the coin thus acting to trip the detent and to move the carrier. When the coin is disengaged from the trip the detent 26 will be in position to engage the next succeeding slot in 50 the indexing plate and the coin will drop through the coin discharge opening 31. When the receptacle has reached this position a pocket containing packages will be 55 located directly over the opening 30 through which opening the packages will fall into the recess 13.

The coin carrier, in the structure herein 60 shown, comprises a base including two plates 38-39, each of which has an overturned lip, 65 said lips 40-41 being spaced apart to permit

the entrance of a coin between them. These lips have flanges 42-43 at opposite ends, said flanges being bent backwardly and the flanges 42 on the lip 40 being located outside of and resting against the flanges 43. The 70 plates 38 and 39 and the flanges and lips may be secured together in any suitable manner, as by electric welding. The plate 38 rests against and slides in contact with the under surface of the cover 29. The 75 opening 34 extends only partially across the plate, the uncut portion of the plate serving as the top of the coin recess 53 in the carrier within which the coin is located when the carrier is moved, the coin dropping through 80 the opening 34 and then, by reason of the inclined position of the parts, rolling into the recess, as shown in Figure 2 of the drawings. As the coin is swept along the inclined surface of the trip 27 it will be pressed 85 against the top of the recess 53, which being a part of the carrier and moving with it, will avoid any sliding action of the coin at its upper edge on a stationary part.

As a means for preventing the insertion 90 of a coin when there are no packages in the pockets in the receptacle, I provide a guard that will be moved at the proper time under the coin slot and prevent the insertion of a coin. In the structure herein shown this 95 guard consists of a finger 44 projecting from a ring 45 secured to the indexing plate 21 and rotating therewith. In adjusting the machine for use, after the pockets have all 100 been filled with packages to be vended, the receptacle will be located with the finger 44 one step in advance of the coin slot 28, and in the position shown in Figure 4. In the successive step-by-step movements of the receptacle, to permit packages to be removed 105 therefrom, when said finger reaches a position underneath the coin slot, the insertion of a coin will be prevented and the purchaser will not, therefore, be subjected to loss of his coin without obtaining value 110 therefor, as it will project as shown in dotted outline in Figure 2, so that it may be removed from the slot 28.

My improved machine is especially 115 adapted for vending goods in variable quantities, in the structure herein shown the pockets being capable of receiving one, two, three or four packages, either number of which it may be desired to vend for a single 120 coin, a pocket being entirely emptied of its goods in each step-by-step movement of the receptacle. In order to denote to the purchaser the amount of goods that may be obtained for a single coin I provide an indicator comprising an indicator disc 46 rotatably mounted on the under surface of the 125 cover 29, said disc bearing numerals, one of which is disclosed through an opening 47 in the cover. This indicator disc may be rotated in any suitable manner to display that 130

numeral to indicate the number of packages to be obtained for the deposit of a coin.

In order to provide for a free sliding movement of the packages, as the receptacle is rotated, and hence a minimum amount of friction to the movement of the latter, I employ ribs 48 on the floor of the case and upon which the packages 52 rest and along which they move as the receptacle is rotated.

As a means of firmly supporting the cover 29 a recess 49 is formed therein at or near its center into which the post 17 extends and if desired the post 17 may be extended through an opening in the bottom of this recess and outside of the cover, such extension 50 being threaded to receive a thumb nut 51. It will be understood, however, that the extension 50 and the thumb nut may be dispensed with if desired, in which case the recess 49 will have no opening to the outside of the cover, the post 17 will terminate within said recess, and the cover will be held closed by the lip at its edge, as shown in Figure 2.

In accordance with the provisions of the patent statutes, I have described the principles of operation of my invention, together with the device which I now consider to represent the best embodiment thereof; but I desire to have it understood that the device shown is only illustrative, and that the invention may be carried out by other means.

I claim—

1. A vending machine including a unit comprising a standard, a case comprising a unit mounted on the extreme top of the standard with its top and bottom parallel faces arranged in an inclined plane, said case being larger in diameter than the standard and disposed transversely on the top of said standard and overhanging it, a receptacle rotatably mounted in the case with its axis in an inclined position, said receptacle having pockets for the reception of merchandise that rests on the bottom of the case, and coin mechanism including a coin operated member for controlling the operation of said receptacle.

2. A vending machine including a coin carrier comprising two plates forming the base of the carrier, each plate having a lip upturned in parallel relation to the lip on the other plate to form a pocket for a coin, means for operating the carrier, means to receive said coin to be operated thereby, and means for securing said plates in relative position.

3. A vending machine including a coin carrier comprising two plates forming the base of the carrier, each plate having a lip upturned therefrom in parallel relation to the lip on the other plate, each of said lips having overturned flanges, the flanges on

one lip resting within and against those on the other lip, means for securing the two plates in relative position, and means to receive and be operated by a coin moved by said carrier.

4. A vending machine including a case, a cover secured to the case, a coin carrier pivotally attached to the under surface of said cover and comprising two plates secured together and having lips extending at substantially right angles thereto and in parallel relation to form a coin pocket, flanges projecting from opposite ends of said lips, the flanges on the lip of the plate resting against said cover receiving between them the flanges on the other lip, said flanges and plates being secured together, and means within the case to receive a coin moved by said carrier to control movement of said receptacle.

5. A vending machine including a coin carrier comprising two plates secured together, one of said plates having an opening therethrough for the passage of a coin and a covered portion at the end of said opening underneath which the coin rests when moved by the carrier, lips located at an angle to each of said plates and in parallel relation to form a pocket for said coin, and means for operating the carrier to move the coin to operate vending mechanism.

6. A vending machine including a case having a coin slot, a receptacle movably mounted in the case and having pockets therein extending in a row entirely around its periphery, a finger movably located independently of said pockets and carried by said receptacle in the case to underlie the coin slot and retain the coin in an accessible position therein, thereby enabling the purchaser to regain his coin, and an operative connection between said receptacle and finger to operate the latter.

7. A vending machine embodying a coin carrier including two plates comprising the base of the carrier, each plate having a lip turned in one direction at an angle thereto and spaced apart to form a coin pocket, each of said lips having flanges bent in another direction at an angle to the lips and secured with their flat faces together to retain the lips in spaced relation.

8. A vending machine embodying a coin carrier including two plates comprising the base of the carrier, each plate having a lip turned at an angle thereto and spaced apart to form the front and back walls of a pocket, each of said lips having flanges bent at an angle thereto and extending in the same direction and secured with their flat faces together to retain the lips in spaced relation, the side edges of said pocket being formed by lips turned from one of said flanges.

CHARLES MAY.
